PREPAY POSTPAY PAYSTATION**Edward J. Benisek, Geneva, Ill., assignor to Automatic Electric Laboratories, Inc., a corporation of Delaware****Filed Oct. 9, 1957; Ser. No. 689,185****1. Claim. (Cl. 179—6.3)**

This invention relates in general to a coin control arrangement and more particularly to a coin control arrangement including several magnets and certain associated equipment of the type generally used in a local prepay telephone paystation for controlling the collecting and refunding of a coin or coins deposited therein.

The invention disclosed herein is a direct improvement on the invention disclosed in the application of Hans Sengebusch, filed September 28, 1955, Serial No. 537,231, now Patent No. 2,905,763 issued September 22, 1959.

The general object of this invention is to provide a means for insuring that the collect magnet coil remains shorted after the collect operation, and to improve the operation of the collect magnet under long loop conditions.

A feature of the invention is that the collect magnet now functions merely as a trip magnet to trip the tilting armature into the collect position.

Another feature of this invention is the reversing of the coin springs and adding only one spring to this assembly whereby it is made to perform a dual function; the original impulse spring shorting feature and the desired shunting of the collect magnet coil when the tilting armature is in the collect position.

In the usual local prepay telephone arrangement, both magnets of a two magnet coin control apparatus are energized for either refunding or collecting a deposited coin, depending on the direction of energization, and must be energized as long as the particular function is to be performed. In the present invention one magnet is effective to collect a deposited coin, and after it is deenergized the coin apparatus remains in the collect position so that any coin deposited thereafter is collected without further apparatus or equipment operation or in other words the paystation is then utilized as a postpay paystation. The other magnet, when energized, operates the equipment to a refund position to refund a deposited coin after which all elements are returned to normal, or if the paystation is in the postpay position, the equipment is thrown into the refund position and then returned to the normal or unoperated position.

As disclosed in United States Patent 1,043,219 issued November 5, 1912, to Forsberg, and as is well known in the telephone art it is customary at a prepay telephone paystation to deposit a coin or coins in a coin chute before a connection can be extended. A deposited coin actuates a coin trigger so that certain electrical circuits are rendered effective to thereby signal the central office over a trunk thereto; prepare an energizing circuit for the coin magnets so that they can dispose of the deposited coin, and also permit operation of the central office equipment to complete the call. The latter condition, of course, being possible only on the deposit of a predetermined coin value as set by the requirement of the system. The coin after operating the coin trigger, which is held in its operated position by an appropriate mechanism, comes to rest on a pivotally mounted coin trap where it is held until the coin magnets are energized to operate an arma-

ture to trip the trap for either collecting or refunding the deposited coin. The energization of the magnets also allows the coin trigger to return to its unoperated position while the circuit is prepared to the coin magnets is maintained by the energized magnets. The described operation is usually controlled by a timed high voltage electrical pulse sent on release of the call over the circuit prepared by the coin trigger to energize the magnets, and the magnets are then deenergized on termination of the pulse. Deenergization of the magnets permits the armature to return to its normal position and the point in the magnet energizing circuit prepared by the coin trigger and held by the energized magnets is then opened. The trap of course pivots to release the coin under control of the operated armature and then returns to normal. Both magnets of the coin control apparatus in the described system are energized, whenever a coin is to be disposed of, and the polarity of the pulse determines whether a collect or refund operation takes place, as the polarity controls the direction in which the magnets are energized.

In the present invention one magnet hereinafter referred to as a collect magnet is associated with the line, and on answer of a call initiated from its associated station it is energized by the reversal of battery on the line, in a manner similar to that described in the application of Lomax filed September 28, 1955, Serial No. 537,240, now Patent No. 2,921,980 issued January 19, 1960.

When energized, the collect magnet causes an armature and the coin trap, operatively connected thereto to be rotated to a position where a deposited coin is collected. Under circumstances which will be described when no coin is on deposit, the trap remains unoperated, however the rotated armature is always retained in the collect position by an appropriate latching arrangement to be described, resulting in the coin trap being arranged so that any coin deposited thereafter falls directly into the coin collect box. The paystation is now arranged in a postpay position. On calls to a local subscriber, placing the paystation in a postpay position is of no significance, but on toll calls where the deposit of substantial load in coins may be required before the call can be completed, it has been found that the magnets at the station may be unable to trip the trap to collect the coins. To avoid this condition, it is of great benefit to place the paystation in a postpay condition so that when coins are deposited preparatory to an operator completing a toll call, they fall directly into the coin hopper and a collect attempt need not be made. A further advantage, due to the fact that heavy coin loads need not be collected in this arrangement, is the elimination of the special high voltage supply and associated equipment at the central office for controlling the collect operation.

A circuit for the refund magnet is prepared, when a deposited coin operates the coin trigger on initiation of a call, or by the operated collect magnet on answer of a call, and on release of the call, either before it is answered or after the collect magnet has been operated, a circuit is completed to energize the refund magnet for a predetermined time. The energized refund magnet operates the armature to a refund position. When the refund magnet is deenergized, the armature is restored to normal so that the paystation once again serves as a prepay type paystation and the point in its energizing circuit prepared by either the coin trigger or the collect magnet is opened. In the event the call was released before being answered the operation of the armature to the refund position operates the coin trap to refund a deposited coin, after which the trap restores itself. On a toll call the refund magnet is initially operated, as soon as the paystation is connected to the CLR trunk, to refund the initially deposited coin. The operator on answering causes the re-

versal of battery to operate the collect magnet which throws the paystation into a postpay condition and also prepares an energizing circuit for the refund magnet to enable its operation on release of the toll call. The refund magnet when again operated then restores all the operating equipment.

The invention, both as to its organization and method of operation, together with further objects and advantages thereof will best be understood by reference to the following specification taken in connection with the accompanying drawings.

Fig. 1 is a side elevation showing the trip armature, tilting armature and the contact arrangement operated thereby.

Fig. 2 is a front elevation of the magnet structure and the contact arrangement with its activating mechanism.

Fig. 3 is a front elevation with a portion of the bracket removed to more clearly show the relationship between the armature, latch, and the retainer attached to the armature.

Fig. 4 is a circuit diagram of a paystation utilizing the mechanism described in the present invention.

A coin deposited in the coin chute causes springs 10 and 11 of the coin spring combination to open slightly to remove a shunt from the dial impulse springs. When the tilting armature operates to collect or refund the coin it causes spring 10 to be deflected still further. This rather considerable movement of spring 10 is being utilized to provide an additional circuit function when operated in the collect position. By connecting spring 10 to one side of magnet "14" and adding mating spring 24, connected to the other side of magnet 14, we obtain the desired shunting of magnet 14 for transmission reasons. This permits the elimination of any contact springs to be operated by magnet 14 and thus make it possible to improve the latching arrangement between the armature 15 of magnet 14 and the tilting armature 17. This eliminates the possibility of magnet 14 not operating fully on a long line and thus not shorting itself out.

An improved anti-sidetone telephone circuit has been incorporated in this paystation in order to improve the transmission characteristics.

When the party hangs up, restoration of the coin-springs to normal re-establishes the talking circuit due to springs 10 and 11 shunting hook switch springs "X."

One method of overcoming this condition is to connect the hook switch in accordance with the conventional prepay paystation circuits. However, this would require the addition of extra equipment. Another method is to add one more spring to the coin spring assembly to permit separation of the collect magnet shunting circuit from the dial impulse spring shunt circuit. However, this would complicate the coin spring pileup and make adjustment more critical.

The preferred solution is that shown in this disclosure. This consists of connecting the "X" hook switch springs between "+L" and the collect magnet, instead of between the induction coil and the collect magnet. This modification will permit the coin springs to function as originally intended.

A coin deposited in and falling through the coin chute (Figure 1) of the local prepay type paystation, strikes the coin trigger projection 2 protruding into the coin channel, and then falls onto the coin trap. The coin trigger 2 is rotated about pivot 3 to allow arm 4 normally resting on the raised portion 5 of the coin trigger to rotate in a counter-clockwise direction about pivot 6 so that its arm 7 causes the projection 8 thereon to bring spring 9 into contact with spring 10 and open the contact between springs 10 and 11 to remove the shunt around the dial springs 12. The circuit effects of the various spring operations may be readily understood by reference to Fig. 4. The coin trigger is prevented from returning to its normal position by arm 4 which now rests against the back surface of the raised portion 5.

Springs 9, 10 and 11 also remain in their respective operated positions. A loop circuit is completed to the central office over the +L and -L conductors, rectifier 13 and dial springs 12, and although magnet 14 is connected thereto it does not operate due to the shunt provided therefor by rectifier 13.

After a connection is extended over the switching equipment and answered by a local called subscriber, battery is reversed on the trunk so that rectifier 13 is no longer effective to shunt current from magnet 14, and it energizes to attract armature 15. Spring 16 normally tends to rotate armature 17 in a clockwise direction about pivots 18 and 18' which is mounted on brackets 19 and 19'. Armature 17, however, is prevented from rotating by detent 20, which is normally retained under latch 21 by spring 22. When armature 15 is attracted due to the energization of magnet 14, detent 20 is moved to a position under the aperture 21' despite the counter-acting tension of spring 22. Armature 17 on being rotated under the action of spring 16 causes the rotation of plate 23. Arm 33 formed with plate 23 and controlled by armature 17 is moved in a clockwise direction to hold springs 9 and 10 in contact, springs 10 and 11 open and bring springs 10 and 24 into contact with each other to shunt current from magnet 14. This is done to prevent magnet 14 from effecting transmission over the loop circuit to the called party. Armature 15 need not be retained in its operated position, as spring 16 rotates armature 17 in a clockwise direction to operate the magnet 14 shunt spring 10 and 24. Simultaneously with the rotation of armature 17 in a clockwise direction plate 23 operatively controlled thereby is likewise rotated. An arm 25 formed integral with plate 23, is also rotated to move pin 26 in a corresponding arc. The plate which supports the coin trap is now caused to rotate to a position such that the coins are deflected into the collect chute of the pay-station. The coin trap is rotated about 27 due to the weight of the coin over-balancing counter-weight 28 and the deposited coin guided by the position of the deflector plate falls into the collect box and is thereby collected. The trap returns to its unoperated position due to the action of weight 28, but any coin now deposited over-balances the weight and rotates the trap so that the coin falls directly into the collect box. The circuit to the refund magnet 29 is completed through neon tube 30 and relay 31 to ground from +L line initially on release of the call by a timed high voltage positive pulse, applied over the line conductors.

Energization of refund magnet 29 attracts armature 17 in a counter-clockwise direction against the tension of spring 16, aided by spring 32. When aperture 21' is disengaged from detent 20, spring 22 returns detent 20 to its normal unoperated position. Contacts 19 and 24 open to remove the shunt from magnet 14. Armature 17 operates plate 23, arm 25, pin 26 and the deflector plate as before described with the exception that they are now operated in the opposite direction. As no coins are on deposit at this time the coin trap does not rotate nor is a refund made. In the refund position cylindrical portion 34 of arm 33, which is operatively controlled by armature 17 through plate 23, is forced against 7 and rotates arm 4 in a clockwise direction to disengage 4 from the raised portion 5 of the coin trigger 2. Springs 9 and 10 are maintained in contact while 34 is passing through its neutral position as arm 7 holds bushing 8 against spring 9 until 34 strikes 7 to pivot 4 in a clockwise direction. The coin trigger now returns to its normal unoperated position as arm 4 is out of engagement with 5, while springs 9 and 10 are kept closed and springs 10 and 11 kept open by 34 which was rotated in a counter-clockwise direction. Wire spring 35 in its final position limits the travel of the coin trigger 2 to ensure that portion 5 is properly placed under 4. At the end of the time pulse, winding of magnet 29 is deenergized and armature 17 is rotated in clockwise direction under the influence of spring

16, however, it is prevented from rotating beyond its equilibrium position when catch 21 strikes detent 20. Simultaneously 34 is moved away from spring 9 to allow springs 9 and 10 to open and contacts 10 and 11 to close and as portion 5 is in its normal position lever 4 comes to rest thereon without closing springs 9 and 10. As springs 9 and 10 open, and contacts 10 and 11 closed the shunt around the dial spring is reestablished to prevent extension of a call from the paystation without the deposit of a coin.

It will be appreciated that on release of an unanswered call a timed pulse is sent to operate refund magnet 29 as described. As magnet 14 was not operated to trip the trap for a collect operation, the deposited coin causes the trap to operate in a direction opposite to that on a collect operation, it is now in position to guide the coin in a refund direction instead of in a collect direction. On restoration of refund magnet 29 armature 17, springs 9, 10, 11 and 24, plate 23, arm 25, pin 26 and the deflector plate are returned to normal, while the coin trap is already returned to normal by the action of weight 35.

A toll call by a subscriber at a paystation of the type described is initiated with the deposit of a coin to operate the coin trigger and close springs 9 and 10 and open contacts 10 and 11 in the manner described. The dialling of a predetermined digit connects the subscriber to a CLR trunk, which in turn automatically sends back a time pulse for operating the refund magnet 29. Refund magnet 29 first throws armature 17 and the trap into the refund position, and the deposited coin is refunded. Contacts 10 and 11 are closed on restoration of winding 29 at the end of the timed pulse, and the coin trap, armature 17 and springs 9 and 24 are returned to their normal position in the manner already described.

The operator on answering automatically reverses battery on the trunk to energize winding 14 to attract armature 15 and allow armature 17 to rotate as previously described under influence of spring 16. Armature 17 when rotated in a clockwise direction under the influence of spring 16, rotates its associated plate 23. Simultaneously 34 in rotating in a clockwise direction engages spring 9 so as to bring it into engagement with 10, open springs 10 and 11 and close springs 10 and 24. The further extension of the connection is now under the control of the operator. Armature 17 and the deflector plate are retained as before described in the collect position so that the trap will now drop any coin deposited at the request of the operator directly into the coin hopper. The paystation being in the postpay position enables the operator to collect the desired value of coins before completing the connection without the necessity of operating a coin magnet and the consequent danger of being unable to collect the coins if the load is too heavy. On release of the call, a timed pulse is sent to energize the

refund magnet 29 and the arrangement is returned to normal as previously described.

In this specification, I have described a coin control apparatus for use in a prepay telephone for the purpose of converting the telephone to a postpay type at certain times, however, as the described arrangement is not limited to such uses, I desire the scope of the invention to be defined by the claim appended hereto.

What is claimed is:

- 10 In a coin control mechanism having a coin deposit chute for receiving coins and a coin trap operable to allow a deposited coin to fall in either of two directions to collect or refund it respectively, a first armature having an arm secured thereto for operating said trap, shunt springs comprising a first spring and a contact, and a second spring and contact normally contacting each other and a third spring and contact, said second spring and contact operable to a first off-normal position to open the normally closed contacts of said first and second 15 spring upon deposit of a coin, a second arm on said first armature effective to operate said second spring to a second off-normal position upon operation of said first armature to a collect position, a first magnet for operating said first armature and said first arm to engage and 20 operate said trap, said trap operated by said magnet for causing a deposited coin to fall in one direction to refund it, a latch normally engaging said armature to prevent operation of the armature in the second direction, a second magnet and means including a second armature 25 controlled by the second magnet when operated for removing said latch from engagement with said first armature to permit operation of the first armature in the second direction, spring means for operating said first armature in said second direction to operate the 30 trap to collect a deposited coin in response to the unlocking of said latch, said second arm on said first armature moved to operate said second of said shunt springs to a second off-normal position to contact said third spring upon the operation of said first armature, circuit means 35 40 including said second and said third springs thereby effective to shunt said second magnet, thereby disabling said second magnet from further operation only after the complete operation of said first armature in said second direction.
